UNITED STATES PATENT OFFICE

REX LA PAYNE AND CLIFTON F. BLAKE, OF GLENDALE, CALIFORNIA; SAID BLAKE
ASSIGNOR TO SAID LA PAYNE

DESIGN FOR A RESTAURANT BUILDING

Application filed March 5, 1932. Serial No. 43,102. Term of patent 7 years.

To all whom it may concern:

Be it known that we, REX LA PAYNE and CLIFTON F. BLAKE, citizens of the United States, residing at Glendale, in the county of Los Angeles and State of California, have invented a new, original, and ornamental Design for Restaurant Buildings, of which the following is a specification, reference being had to the accompanying drawings, forming a part thereof.

Fig. 1 is a front elevational view of a restaurant building showing our new design.

Fig. 2 is an end elevational view of the building.

The rear half of the body of the building is in the form of a half cylinder with a substantially smooth surface and with rounded ends that unite with the correspondingly rounded ends of the front half of the body of the building, thereby imparting to the entire building structure the general shape of a frankfurter or weinerwurst.

We claim:

The ornamental design for a restaurant building as shown and described.

REX LA PAYNE.
CLIFTON F. BLAKE.
